UNITED STATES PATENT OFFICE.

LEVI HAAS, OF CHESTER, PENNSYLVANIA.

RAILROAD-CHAIR.

SPECIFICATION forming part of Letters Patent No. 253,874, dated February 7, 1882.

Application filed July 19, 1881. (No model.)

To all whom it may concern:

Be it known that I, LEVI HAAS, of Chester, in the county of Delaware and State of Pennsylvania, have invented certain new and useful Improvements in Railroad-Chairs; and I do hereby declare that the following is a full, clear, and exact description of the invention, which will enable others skilled in the art to which it appertains to make and use the same, reference being had to the accompanying drawings, which form a part of this specification, and in which—

Figure 1 is a detached view of the chair. Fig. 2 is a side elevation. Fig. 3 is a detached view of the tie. Fig. 4 is a side elevation, and Fig. 5 is a plan view, of my invention.

This invention has relation to improvements in railway-chairs, which may be constructed of T-rail waste, scrap, or other iron, which may answer the intended purpose; and it consists in certain details of construction and arrangement of parts, substantially as hereinafter more fully set forth and claimed.

Referring to the accompanying drawings, A indicates a section of a T-rail forming the foundation or base, and taking the place of the ordinary wood tie, which is objectionable because, among other reasons, it is subject to decay, requiring frequent renewal. The section of T-rail iron A only requires the recessing out of its upper or flanged portion to enable it to serve in the capacity of a chair, as will be readily understood by reference to Fig. 2. The bottom of the recess a is further recessed

at a', which recesses are filled by pieces of wood B piled one upon the other, to form an elastic bearing for the rails. This latter feature, with the securing nutted and bolted plates C for the rails, is the same as that described in a former application of mine. The chairs are connected together at the base or web by rods or bars b, adjustably connected thereto.

This improvement embodies the construction of the base in such manner that it answers the purpose of a tie to the extent of supporting the rail and the chair unitedly, and the expense of its construction is thus lessened.

I claim and desire to secure by Letters Patent—

1. In a railway-chair, the securing-plates C and chair having recesses a and a', in combination with rail-supports A, wooden pieces B, and rods or bars b, substantially as shown, and for the purpose described. 50

2. A railroad-chair adapted to be constructed of waste T-rail iron, provided with rods and bars b, the chair having securing-plates C, and being recessed for reception of wooden pieces B, placed therein, as shown, and for the purpose described. 55

In testimony that I claim the foregoing as my own I have hereto affixed my signature in presence of two witnesses.

LEVI HAAS.
